UNITED STATES PATENT OFFICE.

REINHARDT H. BROWN, OF LAPORTE, INDIANA, ASSIGNOR TO OUTING KUMFY-KAB COMPANY, OF LAPORTE, INDIANA, A CORPORATION OF INDIANA.

CHILD'S VEHICLE.

1,234,725.

Specification of Letters Patent. Patented July 31, 1917.

Application filed July 21, 1916. Serial No. 110,459.

To all whom it may concern:

Be it known that I, REINHARDT H. BROWN, a citizen of the United States, and a resident of Laporte, in the county of Laporte and State of Indiana, have invented certain new and useful Improvements in Children's Vehicles, of which the following is a full, clear, and exact specification.

My invention is concerned with children's vehicles, and is designed to produce a vehicle of the class described that is especially adapted for use either of very young infants that must lie down in the vehicle, as in the ordinary baby-carriage, or for older ones who can sit up, as in an ordinary child's sulky. To this end, my invention consists of a novel vehicle preferably including an adjustable back-rest in combination with a foot-well than can be shoved back beneath the seat when it is used by an older child sitting erect with his feet on the customary foot-rest, or drawn out over the foot-rest and receive the infant's feet suitably wrapped in a blanket when it is so young that it must lie down in the vehicle, or its feet would not readily reach down to the foot-rest when sitting up.

To illustrate my invention, I have annexed hereto three sheets of drawings, in which the same reference characters are used to designate identical parts in all the figures, of which,—

Figure 1 is a side elevation of a vehicle embodying my invention, adjusted for the use of a child that can sit up;

Fig. 2 is a central longitudinal section as seen on the line 2—2 of Fig. 3, adjusted for a baby that must recline in the vehicle;

Fig. 3 is a vertical section on the line 3—3 of Fig. 1;

Fig. 4 is a view of the vehicle as seen on a larger scale and folded up;

Fig. 5 is an enlarged detail of the back-rest mechanism; and

Figs. 6 and 7 are details on an enlarged scale in perspective, and side elevation partly in section, respectively, of the front portion of the foot-well.

While my invention is capable of use with various forms of children's vehicles, I have shown it as applied to a collapsible sulky of the type shown in my application Serial No. 69,792, filed January 3, 1916, of which this application is an enforced division, and in this specification, the non-essential features

will be described somewhat briefly, while the vital features will be described more fully.

The main frame of the sulky in the embodiment shown is generally rectangular in its outlines, and is made up of the two side bars 12, which are connected near their rear ends by the cross bar 13. The rear ends of the bars 12 are curved downward, as seen at 21, and have the small wheels 22 journaled thereon, these wheels serving as a pair of the four supports to hold the sulky in the vertical position shown in Fig. 4, which wheels are used in the customary manner in drawing the sulky up and down over curbstones or steps, the other two supports being formed by the curved ends 15 of the U shaped cross-bar 13.

The seat 23 preferably consists of a substantially square piece of wood or some other strong and light-weight material of suitable thickness, and which may be cushioned, as shown, as much as desired, and the rear edge of this seat 23 is suitably secured to the upper surface of the horizontal bar 24, which has the upturned ends 25, to which are pivoted the rear arms 26 of the side frames or arm-rests, which have the horizontal arm-rests 27 pivoted on the upper ends of the bars 26, and in turn pivoted at their front ends to the vertical arms or levers 28 of the erecting bail, which is pivoted to the inner side of the main-frame tubes 12 at 29, the arms 28 being preferably shaped, as shown, in substantially an ogee curve to bring the horizontal connecting bar 30 constituting the horizontal portion of the bail in proper relationship to the wheel-frames. The front end of the seat 23 is secured to the bar 31 corresponding to the rear bar 24, which bar has the stop lug 32 depending downwardly from its center for the purpose to be hereinafter described. The bars 24 and 31 are riveted at their ends to the horizontal bars 33, which are located directly beneath the edges of the seat, and riveted on these bars 33 are the spring bars 34 having the central horizontal portions thereof in contact with the under side of the bars 33, while their rear ends 35 are curved through substantially three-quarters of a circle and have their ends riveted on the twisted portions 36 of the bar 13. The forward ends of these spring bars 34 have the slightly inclined portions 37, which terminate in the curved

ends 38, corresponding to the rear curved ends 35, but somewhat smaller, and these spring ends 38 are riveted, as best seen in Fig. 2, to a bracket 39 secured to the inner 5 ends of the rivets 29 upon which the arms 28 of the erecting bail are pivoted, the erecting bail being interposed between the tubular sides 12 of the main frame and the vertical portion of the angular brackets 39. 10 By the construction shown, I have secured a very elastic cushioned seat that is held a few inches above the main frame so as to furnish room beneath it for the drawer or foot-well 40, which preferably consists of 15 a rectangular frame made up of the rear rod 41 and a bar 42 bent into a U-shape so as to form the front and sides of the top of the foot-well. The sides of this bar 42 have their upper edges bent to form the hooked flanges 43 which slide in the reversely hooked flanges 44 of the guideway bars 45 secured on the under side of the bars 33, preferably being riveted between said bars 33 and the horizontal portions 34 of the 20 supporting springs. A front portion of the bar 42 has the stiffening member 46 secured to and depending therefrom to form the front of the foot-well, and this member 46 has the horizontal portion 47 extending 25 rearwardly therefrom, while the sides and bottom of the foot-well are formed by the fabric 48 secured to the top of the rectangular frame and inclosing the stiffening portions 46 and 47. This foot-well is held 30 in its closed or unused position by the top of the front contacting with the stop lug 32, while said lug similarly contacts with the bar 41 at the rear of the foot-well to prevent its being accidentally drawn out of 35 the supporting ways. A flexible loop 49 is provided to enable the foot-well to be readily manipulated.

The back-rest 50 is constructed like the body of the seat, and has its sides and top 45 secured in the metal frame 51, which is U-shaped in cross section for most of its length, and is also U-shaped in its general design, the ends 52 thereof, however, being flattened and pivoted on the same rivets 53 by which 50 the side-frame bars 26 are pivoted on the upturned ends 25 of the bar 24. This back-frame is held in a plurality of positions by the bail 54, best seen in Fig. 5, which is preferably made of a heavy wire and is of a 55 general U-shape, it being pivoted at its ends by loops encircling the headed studs 55 projecting outwardly from the upper ends of the side pieces 26 to which they are secured. The back 50 has a flat metal-bar 56 secured to and extending horizontally 60 across the back side thereof below the center, and has the forwardly projecting short arms 57 at its ends. The bail 54 has the upwardly extending portions 58 at 65 its ends connected by the curves 59 with the

normally vertical portions 60, and, as shown in Fig. 5, when the bail is in the full-line position, the back 50, through the ends of the bar 56, is held in a vertical position between the arms 26 and the vertical portion 70 60 of the bail 54, and being thus substantially attached to the arms 26, will be collapsed therewith when the sulky is collapsed. The bar 56 in turn reacts on the bail 50 and holds it in the full-line position, but it will be obvious that when the bail is forcibly pulled up to the dotted-line position shown in Fig. 5, it will be sprung sufficiently to relieve it from the holding action of the flat side of the bar 56 coöperating with the vertical portion 60, and it may then be swung up further so as to release the bail from any confining action of the bar 51, in which position the back can be swung rearwardly either to the extreme limit shown in Fig. 2, 80 where the back rests against the bail, or to an intermediate position, shown in full lines in Fig. 1, where the ends of the bar 56 enter the loops 61 formed in the vertical portion 60 of the bail. Riveted to the inner sides 90 of the side pieces 12 are the rectangular plates 62, having the inturned flanges 63 at their ends, the lower portions of which serve as a hinge for the wheel-frames 64, which are preferably formed of sheet-metal and of 95 a generally triangular shape, having the wheel axles or studs 65 rigidly secured and projecting outwardly from the lower ends thereof to receive the customary wheels 66 mounted thereon. A rod 67 is fastened in 100 the flanges 63 and serves as a pintle for the hinge formed by said flanges and the ears 68 projecting upward from the ends of the wheel-frames 64; and to collapse the wheels 105 automatically when they are released, I may mount on the rod 67 a coiled torsional spring 69, one end of which reacts against the bottom of the plate 62, while the other end reacts against the top of the wheel-frames 64, so that the spring always tends to throw the 110 wheel-frames to the collapsed position shown in Fig. 4. The wheel-frames are provided with cams and hook portions 71, suitably designed to coöperate with the erecting bail 29 to erect the wheel-frames and lock them in 115 their erected position in the customary manner.

Pivoted to the inner edges of the forward portion of the bars 12 by the rivets 74 is a front standard 75, which is preferably 120 formed of a metal bar of substantially U-shape in its general outline except that it has inclined portions 76 near its upper end to narrow the frame so that the pair of bars 79 constituting the frame for the foot-rest 80 125 may be pivoted thereto at 81 at the proper distance apart. The rear ends of these bars 79 are bent somewhat to cause them to diverge, and they are pivoted at said rear ends by the rivets 82 to the lower ends of 130

the levers 28 of the erecting bail. As the parts are collapsed, the standard 75 and the foot-rest and its supporting bars will be folded rearwardly and upwardly between 5 the wheel-frames and the seat, as seen in Fig. 4. While the erecting frame might be manipulated in any suitable manner, I preferably manipulate it by the tongue 83, pivoted in the forward end of the main frame 10 by its forked portion at 87, the forked inner ends of the tongue being connected by the links 88 pivoted thereto to the side pieces 28 of the erecting bail, so that the tongue may be employed as an operating lever to 15 collapse and erect the sulky.

The operation of my invention will be readily apparent. Assuming that it is purchased for the use of a very young baby, in the use the parts are positioned as shown 20 in Fig. 2, where the baby, suitably wrapped up, can be laid on the seat with its head against the slightly inclined back-rest 50, and with its feet wrapped up and resting in the foot-well, which is drawn out to the limit 25 of its possible movement and preferably has its forward lower edge resting on the foot-rest 80, as shown in Fig. 2. In this position, the baby is held in place by the side-arms 27 with sufficient security so that it can be 30 hauled about the same as in an ordinary baby-carriage. When the foot-well is not in use, some of the apparel can be placed therein, and it can be shoved back beneath the seat, as shown in Fig. 1. As the child 35 grows older, and it is desired to have it sit up, the back can be erected completely, as indicated in dotted lines in Fig. 2, or partially, as shown in Fig. 1, and with the foot-well shoved back beneath the seat, as shown 40 in Fig. 1, the child is free to sit up in the cart with its feet supported on the foot-rest 80 in the customary manner.

While I have shown and described my invention as embodied in the form which I at 45 present consider best adapted to carry out its purposes, it will be understood that it is capable of modifications, and that I do not desire to be limited in the interpretation of the following claims except as may be necessary 50 situated by the state of the prior art.

What I claim as new, and desire to secure by Letters Patent of the United States, is:

1. In a device of the class described, the combination with the main frame and a 55 seat supported thereby, of an adjustable back-rest coöperating with the seat, arm-rests at the sides of the seat, a foot-rest below and forward of the seat, and a foot-well adapted to be moved beneath the seat or extended forward over the foot-rest.

2. In a device of the class described, the combination with the main frame and a seat supported thereby, of an adjustable back-rest coöperating with the seat, arm- 65 rests at the sides of the seat, a foot-rest be-

low and forward of the seat, a foot-well adapted to be moved beneath the seat or extended forward over the foot-rest, and connections for collapsing and erecting the foot-rest, back-rest and arm-rests; substantially 70 as and for the purpose described.

3. In a device of the class described, the combination with a main frame and a seat supported thereby, of an adjustable back-rest coöperating with the seat, arm- 75 rests at the sides of the seat, a foot-rest below and forward of the seat, a foot-well adapted to be moved beneath the seat or extended forward over the foot-rest, wheel-frames attached to the main frame, and connections for collapsing and erecting the foot-rest, back-rest, arm-rests and wheel-frames.

4. In a device of the class described, the combination with a main frame and a seat supported thereby, of an adjustable back-rest coöperating with the seat, arm- 85 rests at the sides of the seat, a foot-rest below and forward of the seat, guides beneath the seat, and a drawer-like foot-well adapted to have its upper sides coöperate with the 90 guides.

5. In a device of the class described, the combination with a main frame and a seat supported thereby, of an adjustable back-rest coöperating with the seat, arm- 95 rests at the sides of the seat, a foot-rest below and forward of the seat, guides beneath the seat, a drawer-like foot-well adapted to have its upper sides coöperate with the 100 guides, and connections for collapsing and erecting the foot-rest, back-rest and arm-rests.

6. In a device of the class described, the combination with a main frame and a seat supported thereby, of an adjustable back-rest coöperating with the seat, arm- 105 rests at the sides of the seat, a foot-rest below and forward of the seat, guides beneath the seat, a drawer-like foot-well adapted to have its upper sides coöperate with the 110 guides, wheel-frames connected to the main frame, and connections for collapsing and erecting the foot-rest, back-rest, arm-rests and wheel-frames.

7. In a device of the class described, the combination with a main frame and a seat supported thereby, of an adjustable back-rest coöperating with the seat, a foot-rest below and forward of the seat, guides beneath the seat, a drawer-like foot-well 120 adapted to have its upper sides coöperate with the guides, and a stop coöperating with the rear of the foot-well to prevent its being entirely withdrawn, but permitting its forward end to drop on the foot-rest.

8. In a device of the class described, the combination with running gears including the main frame, of a seat carried thereby and having guide ribs on the under side thereof, and a drawer-like foot-well having 130

coöperating guide-ribs on its upper edges coöperating therewith.

9. In a device of the class described, the combination with running gears including a main frame, of a seat carried thereby and guide-ribs on the under side thereof, a drawer-like foot-well having coöperating guide ribs on its upper edges coöperating therewith, and a stop depending from the front of the seat into the line of movement of the front and rear edges of the top of the drawer.

10. In a device of the class described, the combination with running gears including the main frame, of a seat carried thereby and guide ribs on the under side thereof, springs interposed between the corners of

said seat and the main frame, and a drawer-like foot-well having coöperating guide-ribs on its upper edges coöperating with the 20 guide-ribs on the under side of the seat.

11. In a device of the class described, the combination with the main frame and a seat supported thereby, of means above the seat for holding the child in place, a foot-rest below and forward of the seat, and a foot-well adapted to be moved beneath the seat or extended forward over the foot-rest.

In witness whereof, I have hereunto set my hand and affixed my seal, this 12th day 30 of July, A. D. 1916.

REINHARDT H. BROWN. [L. S.]
